UNITED STATES PATENT OFFICE.

JOSEPH J. SPRENGER AND RASMUS L. SORENSEN, OF INDIANAPOLIS, INDIANA.

HANDLE AND DICE CONTAINER.

Application filed May 21, 1928. Serial No. 279,233.

This invention relates to handle mechanisms particularly designed for use in connection with poker chip trays, and provides a handle construction of the class that may 5 be telescoped or lowered into juxtaposition to the tray, when not in use.

A further feature of the invention is the provision of means for carrying a plurality of dice within the hand engaging portion of 10 the handle construction, and provide visual spaces whereby the dice may be exposed to view.

A further feature of the invention is the provision of removable means for closing 15 the ends of the hand engaging portion of the handle construction.

A further feature of the invention is the provision of frictional means for normally holding the handle construction in extended 20 or telescoped position.

Other objects and advantages will be hereinafter more fully set forth and pointed out in the accompanying specification.

In the accompanying drawing which is 25 made a part of this application,

Figure 1 is a side elevation of the handle construction as applied to use.

Figure 2 is a sectional view thereof as seen in the proximity of line 2—2, Fig. 1.

Figure 3 is a sectional view as seen on line 30 3—3, Fig. 1.

Figure 4 is an elevation of one of the removable closure means for the ends of the hand grip portion of the device, and

Figure 5 is a perspective view of one of the dice to be stored as desired within the 35 handle construction.

Referring to the drawings, similar character references designate corresponding parts throughout, and the numeral 1 indicates fragmentarily a conventional form of poker chip carrying tray, to which is attached a handle construction 2, comprising a hand gripping bar 3 and a pair of standards 4, which are 40 preferably integral with said hand gripping bar.

The bar 3 is substantially square in cross section and hollow to receive dice 5, portion of the walls of said bar being cut out to form 45 visual panel spaces 6, through which the dice are visible. The ends of said bar are normally closed by means of plugs 7, that portion of the plugs entering the bar, being preferably circular in cross section and slightly larger in diameter than the inside distance

between opposite walls of said bar, so as to form a retaining tension with the walls of the bar, when entered therein, it being understood that the walls are conveniently adapted to be thus sprung outwardly a slight amount, 60 by said plugs when in place.

The standards 4 extend downwardly through bores 8 in the tray 1 and are vertically slideable therein, the lower ends of the standards having shoulders 9 thereon to prevent the standards being entirely withdrawn from the bores, the upper ends of the bores having eyelets 10 therein through which the standards slide. The standards 4 are preferably slightly outwardly inclined from their 70 connection with the bar 3 as indicated by dotted lines 11 in Fig. 1, so that they will exert friction against the walls of the eyelets 10 and thus hold the bar 3 at any adjusted position vertically above the tray 1. 75

When the tray is not in use, the handle construction is preferably pushed downwardly until it rests in close proximity to the face of the tray 1, but when the tray is to be transported, the handle construction is moved upwardly manually as shown, the frictional engagement of the standards 4 against the walls of the eyelets 10 holding the bar in elevated position.

When the dice 5 are to be used, one or both 85 of the plugs 7 are removed, then the dice may be extracted from the bar 3. The bar 3 is preferably of an outline to snugly receive the dice, and by properly attaching the same to the standards 4 it forms a convenient grip 90 for the hand, as when the tray is to be carried about. It will be further seen that a convenient receptacle for the dice is formed without adding much to the cost of the device and by providing the visual spaces 6, all 95 the dice within the handle will be visible from either side of the gripping bar, and a dice of a certain desired denomination may be withdrawn by the removal of whichever one of the plugs 7, it is nearest. The bores 8 develop abruptly into a larger diameter at their lower portions 12, thus forming the shoulders 13 against which the shoulders 9 are drawn to stop the standards 4 in working position when withdrawn.

While the description and drawings illustrate in a general way certain instrumentalities which may be employed in carrying the invention into effect, it is evident that many modifications may be made in the various de- 110

tails, without departing from the scope of the appended claims, it being understood that the invention is not restricted to the particular example herein described.

5. What we claim is:

1. In a handle construction, a hollow gripping bar, standards connected therewith arranged for frictional engagement with an object in which they are entered, and closure 10 means for the ends of said gripping bar.

2. In a handle construction, a hollow gripping bar square in cross section, adapted to contain dice, standards connected therewith having frictional engagement with an object 15 in which they are entered, said gripping bar having panel type openings for observing the contents of the bar, and removable closure means for the ends of said bar.

3. In a handle construction, a hollow gripping bar having visual spaces formed therein, standards connected with the gripping bar, and eyelets through which said standards extend, said standards having frictional engagement with said eyelets for retaining said 25 gripping bar in elevated position.

4. In a handle construction, a hollow gripping bar adapted to receive and house dice, the walls of said bar having visual spaces through which said dice may be observed, 30 standards integral with said bar and slightly inclined for forming frictional engagement

with parts in which they are mounted, for holding said gripping bar in various adjusted positions, and removable means for closing the ends of said gripping bar.

35

5. The combination with a tray having bores therein, of a handle construction, comprising a hollow gripping bar, standards connected therewith, said standards entering said bores and being slightly inclined from 40 their outer to their inner ends, and eyelets in the outer ends of said bores through which said standards extend and have frictional engagement.

6. The combination with a tray having 45 bores therein, of a gripping bar substantially square in cross section and having visual spaces longitudinally thereof through which objects within the gripping bar may be viewed, standards projecting from said gripping bar into said bores, eyelets through 50 which said standards extend, said standards being slightly inclined for forming frictional engagement with said eyelets, and means for limiting the outward movement of 55 said standards.

In testimony whereof, we have hereunto set our hands on this the 15th day of May, A. D. 1928.

JOSEPH J. SPRENGER.
RASMUS L. SORENSEN.
